PAPERBOARD FORMING MACHINE

Bernard A. Malkin, Lachine, Quebec, Canada

Application January 7, 1950, Serial No. 137,375

8 Claims. (Cl. 92—43)

1

This invention relates to improvements in cylinder-mold machines employed in the pulp and paper industry for the manufacture of paper and paper pulp products.

The salient feature of the invention consists in the provision of an improved type of cylinder-mold on which the stock is formed into a sheet of desired thickness.

As compared with conventional cylinder-molds, one important advantage of the improved cylinder-mold provided in accordance with the present invention is that it enables thin sheets of excellent formation to be produced from thicker stock than has heretofore been considered feasible and thus reduces the cost of production by reducing the amount of dilution-water and power required.

Another advantage of the improved cylinder-mold is that it may be used in a variety of ways to provide a wide range of different types of installations designed to meet different operating conditions or the requirements of different mills. It may be used with or without suction boxes and with or without a vat. For example, when one or more suction boxes are arranged within the improved cylinder-mold, the vat may be dispensed with and replaced by various other means for feeding the stock to the forming surface of the mold. The improved mold, either with or without suction boxes arranged therein, may also be used to advantage in a conventional vat as a replacement for the conventional type of cylinder-mold. When the improved mold, without suction boxes, is installed in a conventional vat as a replacement for the conventional cylinder-mold the improved mold may be immersed in stock supplied to the vat circle in the conventional manner. In this case the improved mold provides a more rigid sheet-forming surface than the conventional mold and may, under certain circumstances, have other advantages. When the improved mold, with one or more suction boxes arranged therein, is installed in a conventional vat as a replacement for the conventional mold, the stock may be supplied to the vat circle and picked up by the mold in the usual manner. In this case the improved mold provides a desirable rigid sheet-forming surface and the effective suction applied through the suction boxes may be varied in accordance with various factors, such as variations in the nature and density of the stock, to control the thickness, formation and other characteristics of the sheet. Alternatively, when the improved mold, with one or more suction boxes arranged therein, is installed in a conventional vat as a replacement for the

2

conventional mold, the stock may be fed to the forming surface of the mold independently of the vat circle. This may be accomplished, for example, by forcing the stock through an approach passage to an apron plate positioned so that the stock flows over the apron plate onto an upper portion of the cylinder-mold which is travelling over the suction box or boxes arranged within the mold. This latter arrangement, due

- 10 to the provision of the suction box or boxes and to the fact that the improved mold affords a better type of forming surface than the conventional mold, provides an improved cylinder mold machine which is capable of handling stock at 15 higher densities and feed velocities than is possible with conventional types of cylinder-mold machines. It also lends itself to the use of improved means for controlling the flow and distribution of the stock delivered to the forming 20 surface of the mold.

Proceeding now to a more detailed description of the invention reference will be had to the accompanying drawings in which—

Fig. 1 is a top plan view of an apparatus embodying my invention.

Fig. 2 is a vertical sectional view through the apparatus shown in Fig. 1.

Fig. 3 is an elevational view of the front end of the apparatus.

Fig. 4 is a transverse sectional view of the apparatus taken along the lines 4—4 of Fig. 2.

Fig. 5 is an enlarged fragmentary view of one end of the cylinder mold.

Fig. 6 is an enlarged detail view of a fragment of the outer surface of the roll shown in Fig. 5.

Fig. 7 is a sectional view taken along the lines 7—7 of Fig. 6.

Fig. 8 is an enlarged detail view taken between the lines 8—8 of Fig. 5.

Fig. 9 is a detail view in elevation of the gate assembly.

Referring more particularly to the drawings, 5 generally indicates a vat including a vat circle 5a which may be of a conventional construction and 6 a cylinder mold having outer bearing surface bands 7 adjacent its front and rear ends. The mold is supported for rotation in the vat by the bands 7 on bearings 8 carried by front and rear ends 9 and 10 of the vat. An external gear 11 secured about the rear end of the mold adjacent rear bearing band 7 meshes with a pinion 12 mounted on the rear end 10 of the vat. The pinion is power driven by a motor (not shown) suitably coupled thereto, as indicated at 14, for rotation of the mold through gear 11.

55 Stock is supplied under pressure from a source

(not shown) to an approach passage 15 through a supply pipe 16. An adjustable flow deflector 17 in the upper section of approach passage 15 regulates and directs the flow of stock to an apron 19 which carries the stock to the surface of the cylinder mold. Apron 19 is confined at its ends by pond plates 19a. An adjustable gate assembly 20 regulates the stock flow over the apron and on to the mold. Conventional outside deckles 21 define the maximum width of the sheet on the mold surface.

The cylinder mold 6 comprises a hollow shell provided with openings 25 between longitudinally extending ribs 26 on the outer surface over which a wire covering, generally indicated at 27, is placed. The details of the openings and the arrangement of the wire covering are hereinafter more fully described. The cylinder mold is arranged for co-action with an endless felt 28 which passes between the mold and a couch roll 29 pivotally mounted on a bracket 30. The pressure of couch roll 29 on felt 28 causes the felt to pick up the formed sheet of stock fibres from the mold. The couch roll is disposed in such relation to the top of the cylinder mold that the felt contacts with the mold under pressure and picks up the formed sheet from the mold after it has passed over the mold. An oscillating shower pipe 31 is arranged across the machine so that its spray washes the outer surface of the mold. A second shower pipe 31a with adjustable angle of spray is arranged to spray the underside of the apron to prevent any stock fibre accumulating thereon. Passages 32 at the ends of the mold connect with white water collection chambers 32a at the ends of the vat which are drained by any suitable cross pipe 33. Excess white water is also drained directly from vat circle 5a, if desired, through conventional valves 34 communicating with the cross pipe 33. Cross pipe 33 is drained through a central passage 33a.

A suction box 35 having wheels 36 mounted at the rear end is slidably inserted into mold 6 through one end thereof. The suction box is provided with two separate suction compartments 37 and 38 so that the amount of vacuum may be varied as required. The upper ends of compartments 37 and 38 are provided with outer longitudinally extending deckle holders 40 and 41 which have deckle packings 42 and 43 mounted therein for confining the breadth of the suction opening. An intermediate longitudinally extending deckle holder 44 having a deckle packing 45 mounted therein, separates the two compartments. End deckle holders 46 having deckle packings 47 mounted therein, extend arcuately across the upper end of the compartments for confining the length of the suction opening.

The suction box is provided with front and rear suction box extensions 50 and 51 respectively, which are suitably secured to the ends thereof. Extensions 50 and 51 are provided with end closures 52 and 53. Front and rear caps 55 and 56 for vat 5 are slidably fitted over the front and rear suction box extensions 50 and 51. The caps are respectively supported by the front and rear ends 9 and 10 of the vat and bolted thereto. Lifting rings 59 and 60 at the top of caps 55 and 56 provide means by which the caps may be handled. Suction box 35 is rotatable relative to caps 55 and 56. The box is secured against lateral displacement by a shoulder 63 on rear extension 51 which is butted against one side of the fixed cap 56 and a worm and quadrant assembly 65, 75

the worm being carried by the cap and the quadrant being secured about the periphery of extension 51 in butting engagement with the remaining side of said cap. The suction box may be rotated in order to obtain the correct operating position for various products. Rotation is effected through the worm and quadrant assembly 65.

A shower pipe 70 extends lengthwise of the suction box and is suitably secured to its outer surface by brackets 71 so that, when the box is in its position shown in Fig. 4, the cylinder mold will be sprayed from its inner surface to the outside so as to clean the cylinder mold prior to its passage over the suction surface of the box. A lead pipe 72 extending through closure 53 of rear suction box extension 51 is connected to one end of shower pipe 70 and at its outer end to a suitable source of water supply (not shown). A nipple connection 75 is connected at one end through opening 71 in the side wall of rear extension 51 to the suction compartment 38. Nipple 75 is connected at its outer end through flexible hose member 79 to a vacuum pump (not shown). A similar connection is made between suction compartment 37 and a vacuum pump (not shown) through opening 78 in extension 51. The flexible hose members permit rotation of the suction box without disconnecting the vacuum lines.

Front suction box extension 50 is provided with a dual pipe elbow 81 having separated openings 82 and 83 communicating the suction compartments 37 and 38 respectively through suitable passages in the side wall of extension 50 for discharge of the white water from the suction box. Elbow 81 is suitably arranged about front extension 50 to permit rotation of said extension relative to the elbow. Sealing rings 85 in channels 86 about the inner surface of the elbow provide sealing means between the adjacent surfaces of the elbow and extend along the side edges of the elbow. Overflow pipes 88 are conventionally arranged to control the level of the white water in the vat when such control is desirable.

The approach passage 15 is connected at its base 90 to the stock supply pipe 16 and is arranged at one side of the vat 5. The inner side wall 92 of the approach passage is directed inwardly toward outer side wall 93 from the base to provide a restricted throat 94 in the upper section with the inner wall flaring outwardly from the restricted throat to meet the forward end of apron 19. The deflector 17 is elongated in section, tapering from its upper rounded end 95 to its lower rounded end 96. The deflector is arranged lengthwise of the approach passage with its lower end 96 projecting toward the restricted throat 94 and is carried at its ends by adjusting mechanisms comprising bearing blocks 97 arranged for vertical sliding movement in guide rails 98 mounted on the vat end walls. A wheel and screw 99 threaded in bearing blocks 97 provides the vertical adjustment. A quadrant 100 carried by block 97 and connected to the lower portion of deflector 17 permits angular adjustment of same. With this arrangement, the stock flow to the apron and thence to the cylinder mold, may be suitably regulated without altering the stock head. This is particularly desirable when the consistency of the stock fibres is changed. Moreover, regulation of the deflector can be effected without stopping the forming operation, and, in fact, such regulation is more effective during operation for the reason that the results will appear as the sheet is drawn off the mold.

The adjustable gate assembly 20 is arranged

lengthwise of the vat over the apron 19 and is supported for vertical adjustment by wheel and screw members 102 at opposite ends. The screw portion of member 102 is threaded through the gate so that rotation of the screw causes the gate to move vertically toward or away from the upper surface of the apron to regulate the flow of stock over the apron to the cylinder mold. A pair of adjustment plates 103 are pivotally secured at their inner ends, as indicated at 104, to the centre of gate 20. The outer ends of plates 103 are secured for adjustment to screws 105 carried by the outer ends of the gate. It frequently happens that the fibres in the stock flow become more concentrated at the outer edges, with a resulting unevenness in the sheet formed thereby. By adjusting the outer ends of plates 103 through the medium of screws 105, any desired quantity of the fibres may be directed toward the centre prior to deposit on the surface of the cylinder mold.

As previously pointed out the cylinder mold shell is provided with openings 25 between longitudinally extending ribs 26 on the outer surface. The outer surfaces of ribs 26 are spirally grooved, as indicated at 106, to permit spiral winding of a wire 107 forming the base of wire covering 27, about the circumference of the mold at approximately $\frac{1}{4}$ " pitch. The wire is soldered or otherwise secured in grooves 106 at intervals to prevent unwinding or other displacement of the wire from the grooves. Inner and outer wire mesh 108 and 109 are then successively placed over the wire coil 107. The ends of the outer wire mesh are lapped over end rings 110 and secured by clamping rings 111 which are butted against rings 110 and fastened in place by suitable bolts 112 or other suitable means. Rings 110 also serve to close the ends of the lengthwise drainage channels 114 formed between ribs 26.

The openings 25 in the shell are preferably arranged in staggered series along the alternate channels 114 with the bore of each opening in offset relation to the radius of the shell for drainage of the channels. The offset is such that the bottom of each opening will be slightly in advance of the upper end. The particular advantage in offsetting the openings is that greater quantities of water can be drawn off from the channels. This is caused by the fact that the water passing through the mesh from the stock tends to follow the direction of rotation rather than to flow at right angles to the direction of rotation. The angular disposition of the suction openings also serves to increase the efficiency in the wash of the cylinder by shower pipe 70.

It has been indicated heretofore, that my improved cylinder-mold may be employed in a variety of ways to provide a wide range of different types of installations designed to meet different operating conditions or other requirements. It may also be used with or without suction boxes and with or without a vat. In the appended drawings, I have shown, for illustrative purposes, a board forming machine including my improved cylinder-mold mounted in a vat assembly of a conventional type, a suction box assembly removably fitted in the ends of the vat and extending through the mold shell, and a stock delivery assembly attached to the vat including an approach passage, gate assembly and apron.

In the particular adaptation of my improved cylinder mold to the conventional vat assembly, as shown in the drawings, substantially all of the component elements of the board forming ma-

chine bear a cooperative relationship with one another. Certain of the elements, however, are not necessarily employed in the prescribed manner for which they were originally intended.

5 Also certain elements may be removed, if desired, without impairing the efficiency of the board forming operation.

To operate the board machine, suction box 35 is adjusted in the mold shell so that the outer deckle of suction compartment 38 lies opposite or relatively close to the plane of the apron 19. The degree of closeness is dependent on such contributing factors as the stock flow, the stock consistency, the speed at which the mold is driven, the vacuum applied to the suction box and/or the type of sheet required. The head of the incoming stock through the approach passage 15 is controlled adjacent the restricted throat 94 by the deflector 17 which is vertically and tiltably adjustable by the wheel and screw mechanism 99 and by the quadrant 100 respectively to regulate the flow of stock to the gate assembly 20, which, in turn, distributes the flow over the apron 19 to the revolving cylinder mold 6. The suction in compartment 38 tends to lay the stock fibres flatly on the wire mesh and at the same time to draw off a substantial amount of the water in the stock which is drawn into channels 114 and thence through openings 25 in the mold. The angular disposition of openings 25 in relation to the rotation of the mold and the direction of carry of the stock tends to accelerate the withdrawal of the water through the openings in the mold since it minimizes any baffling effect against the walls of the opening which would be encountered if the openings were arranged radially of the mold. The withdrawal of the water from the fibres on the screen is continued as they are carried over the second suction compartment 37. The thus formed sheet is then lifted from the mold by pressure contact of felt 28 brought about by the action of couch roll 29 thereagainst.

Although I have shown a dual compartment suction box, in many instances a single compartment suction box will serve the needs. However, I find that the dual type is more universal since it can be regulated to provide uniform suction throughout or to apply high and low vacuum to either compartment at varying degrees to meet specific requirements. As a further alternative the suction box may be divided into any suitable number of compartments to meet the requirements of specific installations.

55 The flow deflector 17, being mounted for vertical adjustment in the approach passage, can be moved into and out of the restricted throat area, indicated at 94, to regulate the volume and pressure of stock flow. Similarly the pivotal mounting of the deflector permits different positions of adjustment in the passage including one extreme position in which all the stock is caused to flow in an inclined direction over one side of the flow deflector toward the gate, a second extreme position in which all of the stock is caused to flow in an oppositely inclined direction over the opposite side of the flow deflector toward said gate, and various intermediate positions in which the flow deflector serves to divide the flow of stock toward the gate 20 into two streams of varying quantities flowing over opposite sides of the flow deflector. With this adjustable flow deflector a flow of stock can be delivered through the approach passage to meet any specification and can be modified at all times to compensate for any

variations in the stock supply to the approach passage.

Gate 20 is raised or lowered by screw members 102 to regulate the density of the stock flow from the approach passage to be distributed over apron 19. If desired, this distribution may be further regulated by means of adjustment plates 103 carried by gate 20, by raising or lowering said plates at their outer ends, in the manner heretofore described, to distribute the fibres in the stock more evenly across the apron before it reaches the mold surface.

Showers 31, 10 and 31a are strategically placed to wash the outer and inner surface of the mold and the under side of apron 19 to clear any stock fibres passing beyond the exposed surface of the suction box compartments.

In the particular application of the invention above described, the vat circle 5a catches the wash and any excess water carrying it to the collection chambers 32a through valve openings 34, where it is discharged through cross pipe 33. The conventional overflow pipes 88 serve no useful purpose in this application and could, therefore, be removed.

My improved cylinder mold in its application as a suction type board forming machine may be used in a conventional vat without my stock delivery and apron assembly. The stock is conventionally supplied to the vat circle immersing the mold therein, and is picked up by the revolving mold in the usual manner. In this event the overflow pipes 88 serve to maintain the level in the vat circle in a conventional manner, the improved mold provides a rigid sheet forming surface and the effective suction applied through the suction box compartments may be varied in accordance with various factors, such as variations in the nature and density of the stock, to control the thickness, formation and other characteristics of the sheet.

In another application of my improved cylinder mold as a suction type board machine, the vat may be dispensed with, mounting the mold for rotation on suitable frames with one or more suction boxes arranged within the mold. Various means for feeding stock to the forming surface of the mold may be employed, such as the approach passage hereinabove described and an apron having pond plates at either side to carry the stock onto an upper portion of the mold which is travelling over the suction box or boxes within the mold. This arrangement, due to the provision of the suction box or boxes and to the fact that the improved mold affords a better type of forming surface than the conventional mold, provides an improved cylinder-mold machine which is capable of handling stock at higher densities and feed velocities than is possible with conventional types of cylinder-mold machines. The arrangement, when employing my particular stock feed assembly, also lends itself to the use of the various previously outlined improved devices for controlling the flow and distribution of the stock delivered to the forming surface of the mold.

A still further application of my cylinder-mold may be as a replacement for the conventional non-suction type of cylinder-mold. When the improved mold, without suction boxes, is installed in the vat as a replacement for the conventional mold, the improved mold may be immersed in stock supplied to the vat circle in the conventional manner. In such a case my improved mold provides a more rigid sheet-forming

surface. The channels 114 beneath the raised mesh and the angularly disposed openings 25 in the mold surface provide rapid drainage of the water from the fibres on the mold surface.

Alternatively, the stock may be directly fed to the forming surface of the mold independently of the vat circle. This may be accomplished, for example, through the medium of my stock feed assembly, delivering the stock through the approach passage, over the apron and onto the upper portion of the mold surface. The vat circle serves to catch all of the drained water and excess stock which is carried away through the ends of the mold as well as through suitable drainage openings in the vat circle.

I claim:

1. A paper making machine of the character described comprising a foraminous cylinder-mold, a horizontal apron having its inner edge extending horizontally along and positioned close to the ascending side of the cylinder-mold so that stock delivered over said apron to the cylinder-mold is formed into a web or sheet on the portion of the cylinder-mold which is travelling upwardly from said apron, pond plates extending upwardly from said apron and serving to laterally confine the stream of stock delivered to the cylinder-mold over said apron and a suction box arranged in the cylinder-mold so that the suction area or areas of said suction box face toward and underlie that portion of the cylinder-mold which is travelling upwardly from the apron.

2. A paper making machine as set forth in claim 1, including means mounting said suction box for rotation about a horizontal axis and adjusting means connected to said suction box for rotating the latter about said axis to various positions of angular adjustment with reference to said cylinder-mold and said apron.

3. A paper making machine as set forth in claim 1, in which the cylinder-mold includes a metal shell provided with rows of drainage openings extending from the inner to the outer surface of said shell, said drainage openings being arranged in parallel rows extending longitudinally of the shell and being inclined so that the inner ends of said openings are offset forwardly of the outer ends in the direction of rotation of the cylinder-mold.

4. A paper making machine as set forth in claim 1 comprising a main vertically disposed slice plate positioned directly above the apron and extending between said pond plates in spaced relation to the adjacent ascending side of the cylinder-mold, and slice plate adjusting means supporting said slice plate and operable to adjust the slice plate to and from the upper surface of said apron.

5. A paper making machine as set forth in claim 1 comprising a main vertically disposed slice plate positioned directly above the apron and extending between said pond plates in spaced relation to the adjacent ascending side of the cylinder-mold, slice plate adjusting means supporting said slice plate and operable to adjust the slice plate to and from the upper surface of said apron, a pair of auxiliary slice plates having their inner ends pivotally secured to the central portion of the main slice plate adjacent the lower edge of the latter and adjusting means connected between said main slice plate and the outer ends of the auxiliary slice plates and operable to swing the auxiliary slice plates downwardly to inclined positions projecting below the

70 lower edge of the main slice plate.

6. A paper making machine as set forth in claim 1, including a vertical approach passage having a stock inlet at its lower end through which stock is delivered to said passage and having a stock outlet at the upper end through which stock passes horizontally from said passage over said apron and is delivered radially to that portion of the cylinder-mold which is travelling upwardly from said apron, said approach passage being bounded at the outer side by a straight vertical outer side wall extending above the apron and being bounded at the inner side by an inner side wall comprising relatively inclined upper and lower wall sections, said upper wall section inclining downwardly and outwardly from the outer edge of the apron toward the outer side wall of said approach passage to provide the latter with a constricted throat located below the apron, said lower wall section inclining upwardly and outwardly toward said outer wall section and having its upper end joined to said upper wall section at said constricted throat, and a flow deflecting and throttling member arranged in the approach passage above but immediately adjacent said constricted throat, and means mounting said flow deflecting and throttling member for swinging movement about a horizontal axis lying parallel with the outer wall of said approach passage and passing through the flow deflecting and throttling member intermediate the upper and lower edges of said member.

7. A paper making machine comprising a foraminous cylinder-mold mounted to rotate about a central horizontal axis, means for rotating said cylinder-mold, a horizontal apron having its inner edge positioned close to and extending along the ascending side of the cylinder-mold so that stock delivered over said apron to the cylinder-mold is formed into a web or sheet on the portion of the cylinder-mold which is travelling upwardly from said apron, pond plates extending upwardly from said apron and serving to laterally confine the stream of stock delivered

- over the apron to said cylinder-mold and a vertical approach passage having a stock inlet at the lower end through which stock is delivered to said passage and having a stock outlet at the upper end through which stock is delivered over said apron and directed radially against the portion of the cylinder-mold which is travelling upwardly from said apron, said approach passage having the greater portion of its length disposed below said apron and being shaped to provide a flow passage gradually decreasing in area from the stock inlet to a restricted throat portion located beyond the apron and then gradually increasing in area from said throat portion toward the outer edge of said apron, and a pivotally mounted flow deflector located in said approach passage above but immediately adjacent the constricted throat portion of said passage.
- 10 8. A paper making machine as set forth in claim 7, including a vertically disposed slice plate positioned directly above the apron and extending between said pond plates and slice plate adjusting means supporting said slice plate and operable to move said slice plate in a vertical direction toward and away from the upper surface of the apron.
